UNITED STATES PATENT OFFICE.

HARRY E. BARBER, OF BOSTON, MASSACHUSETTS.

RADIATOR SUPPORT.

Application filed August 18, 1922. Serial No. 532,615.

To all whom it may concern:

Be it known that I, HARRY E. BARBER, a citizen of the United States, and resident of Boston, in the county of Suffolk and State of Massachusetts, have invented certain new and useful Improvements in Radiator Supports, of which the following is a specification.

This invention relates to radiator supports such as are employed to hold a radiator in position adjacent the wall of a room, and it has for its object to provide an improved device of this kind.

Radiator supports of the class to which my invention relates have heretofore been constructed so as to comprise a bracket rigidly attachable to the wall of a room and made with an integral immovable arm projecting therefrom adapted to occupy a position between two of the units of the radiator and under one end, or manifold, thereof to thereby serve as a supporting rest which bears the weight of the radiator. An example of a radiator support of this class is shown and described in U. S. Letters Patent No. 1,175,707 granted March 14, 1916. Radiator supports of this kind as heretofore constructed had the objectionable feature that no provision was made for movement of the radiator under the influence of the expansion and contraction of the pipe lines, and of the radiator itself, with the result that the bracket and the means by which it was fastened to the wall were subjected to injurious strains exerted side-wise against its radiator supporting arm. Also, with the constructions heretofore proposed, it was necessary, when installing the support and radiator, to position the bracket on the wall with great exactness relatively to the radiator, or to exactly position the radiator with relation to the bracket, in order to have the supporting arm register with one of the openings between two of the units. My invention aims to obviate these objectionable features and it consists of a radiator support of the class described having the peculiar features of construction and mode of operation set forth in the following description, the novel features of the invention being particularly pointed out and defined in the claims at the close thereof.

In the accompanying drawings:

Figure 1 is a front elevation of a radiator

support constructed in accordance with my invention.

Figure 2 is a side elevation of the radiator support shown in Fig. 1, the wall to which the support is fastened, and the radiator, being indicated by dotted lines.

Figure 3 is a section on line 3—3 of Fig. 2.

Referring now to the drawings wherein I have shown one embodiment of my invention, 1 represents a cast iron base member provided upon its outer side with horizontal guide rods 2 and 3 near the upper and lower ends thereof, respectively. These guide rods occupy apertures provided in outstanding lugs or ears 4 that are integral with base member 1, each rod being threaded at one end to engage threads provided within the aperture of one of its lugs and provided at its opposite end with a square head 5. Base member 1 is adapted to be fastened to a wall 10 by any suitable means such as an expansion bolt 6 on which the base member is preferably rendered adjustable through the provision of the elongated bolt hole 7 formed in said base member.

To hold base member 1 in vertically adjusted position I may cast the same with teeth 8 adjacent slot 7 and provide the expansion bolt 6 with a washer 9 having complementary teeth to interlock therewith. When the bolt is screwed up tight the base member 1 will be positively locked against displacement relatively to the expansion bolt and wall 10.

Slidably mounted upon the guide rods 2 and 3 is a bracket member 11 made near its upper end with an outstanding hook-shaped arm or rest 12 adapted to extend between two of the radiator units 13 so as to receive upon it the upper manifold 14 of the radiator and thereby support the latter.

In order that the radiator may be adjusted so as to occupy a vertical position and be securely fastened against movement relatively to bracket member 11, I provide the latter with an adjustable abutment screw 15 against which the side of the radiator is clamped by means of a clamping screw 16, the latter having loosely mounted thereon a wedge shaped clamping block 17. The two screws 15 and 16 occupy tapped holes provided in bracket member 11 near the lower end of the latter, the screw 15 being relatively short and adapted to engage the inner side of the radiator as shown in Fig.

3, and the screw 16 being made longer and positioned to extend through the radiator between two of the units with the block 17 engaging the latter so that when said screw 5 is tightened the radiator is clamped securely and immovably between the abutment screw 15 and clamping washer 17.

It will thus be clear from the foregoing description that while the base member 1 is 10 immovably secured to the wall, yet the bracket member is free to slide laterally on guide rods 2 and 3 in a direction parallel with the wall either to permit the rest arm 12 to be manually positioned with relation 15 to one of the openings between the units of the radiator when installing the latter, or to permit of automatic adjustment of the radiator and the arm 12 on the base member when shifted laterally through the ex-

pansion and contraction of the radiator and 20 pipes connected therewith.

What I claim is:—

A wall support for radiators comprising a single one-piece wall plate formed with a vertical slot intermediate its upper and lower ends to receive a bolt or the like for securing said plate to a wall; a bracket member in front of said wall plate having an aperture at its upper end, an aperture at its lower end and means for fastening a 30 radiator thereto, and two horizontally disposed guide rods on and parallel with said base plate, said rods extending loosely through said apertures and slidably supporting said bracket member. 35

In testimony whereof I have affixed my signature.

HARRY E. BARBER.
